UNITED STATES PATENT OFFICE.

SOPHRONIA T. LEWIS, OF WATERTOWN, NEW YORK.

DRESS-CHART.

SPECIFICATION forming part of Letters Patent No. 321,986, dated July 14, 1885.

Application filed April 5, 1884. (No model.)

To all whom it may concern:

Be it known that I, SOPHRONIA T. LEWIS, a citizen of the United States, residing at Watertown, in the county of Jefferson and State 5 of New York, have invented a new and useful Dress-Chart, of which the following is a specification, reference being had to the accompanying drawings.

This invention has relation to pattern-charts 10 or combination-squares used in drafting patterns of ladies' and children's garments, or any garment that may be made by taking measures of the waist and sleeve; and it has for its object to produce a pattern-chart or 15 combination-square by which the drafting may be done, at the same time saving time and study in cutting perfectly-fitting garments, the tables on the chart being simple and the chart or square being of a convenient size for 20 handling; and the invention consists in the novel pattern-chart or combination-square hereinafter fully described, and particularly pointed out in the claim.

Figure 1 is a plan view of the improved 25 combination-square, showing the tables for the waist and bust measures—waist-line, center-back, side-body, gore, back-neck, and dart tables. Fig. 2 is a plan view of the other side of the combination-square, showing the front-neck and sleeve tables; Fig. 3, a plan of the 30 draft of the front of a garment. Fig. 4 is a draft of the center back. Fig. 5 is a draft of the side body. Fig. 6 is a draft for the gore. Fig. 7 is a draft of front with one dart. Fig. 8 is a draft of plain back. Fig. 9 is a 35 draft for children's garments. Figs. 10 and 11 (marked Diagram 1, Diagram 2) are drafts of the back, with seam to the shoulder. Fig. 12 is a draft of a common sleeve; Fig. 13, a 40 draft of a gathered sleeve; Fig. 14, a draft of under part for gathered sleeve; Fig. 15, draft of yoke without a seam.

Referring by letter to the accompanying 45 drawings, S designates my improved pattern-chart or combination-square, which is twelve inches long by five inches wide at one end, and two and one-half inches wide at the other end. Its straight edges are graduated into inches and fractions of inches. The curved 50 slot V is also provided with a graduated scale at its inner edge on one of its faces, marked "Front Neck," and having dots numbered from

1 to 20, as shown in Fig. 2. On one face of the combination-square is provided the front-bust scale, which has the A corner and the E corner marked, and is divided into one-eighth inch gradations, and at the four-and-one-half-inch mark is marked with the number 20, which is the commencement of a series terminating in the number 50, arranged one-fourth inch apart. The five-inch edge on this face is provided with the back-neck scale, which is graded into inches, one-fourth inch, and one-tenth inch, and mark tenths. The other end is also graduated into one-eighth 55 inches. This face of the combination-square is provided with a table for the waist-lines marked "Waist Lines" thereon, and comprises the "center-back" table, "side-body" table, and "gore" table, located along the twelve-inch rule. Above these and parallel therewith is another table, marked "Bust and Waist Measures." Above this latter table and parallel therewith is a double-column table, marked "Dart Table" at the left end, across the end, 60 and marked "Index Fig." in the upper column, and "Darts" in the lower one of these two columns of figures and fractions. On this face of the combination-square at the one-inch mark the letter "F" appears. At the point 65 nearest the curve portion V is printed the letter "D," and on the curved portion V are printed the letters "X" and "Y" and the mark "11," located at the points shown. On the other face of the combination the square 70 is provided with the "B" corner, "G" corner, and "K" corner. The point "D" also appears on this face, and a point, "C," at the end of the curve in line with the half-inch mark on the five-inch scale. The two-and-one-half-inch scale also appears on the short end 75 of the square on this face. The twelve-inch edge is provided with a scale of one-eighth inch, numbered from 20 to 50, commencing at the three-and-seven-eighths-inch mark, 80 and is marked "Back Bust." The "front-neck" scale on this face has already been described. The sleeve-table is printed or otherwise made on this face, and is marked at the left "Sleeve Table." The columns of figures 85 which compose the sleeve-table run parallel with each other and in the direction of the length of the square. The upper column of the sleeve-table is marked "Armseye Meas- 90 95 100

ures," and contains the numbers constituting the table for said measures. The columns next below are marked "Common Sleeve" above them. Across them at the left of the figures 5 constituting the table is the word "Upper," and near this word are the abbreviations "T.S." and the word "Line," which, when construed, means "Top Sleeve-Line." Immediately under the letter "T." appear the letter "E," and 10 the ditto-marks—thus "E.,"—which is read "Elbow Line." The columns next below have the letters "T. S." and "E," and the ditto-marks, and the cross-word "Under" with the table for the under part of the common sleeve. 15 Below the table for the common sleeve are the tables for the gathered elbow, marked "Gathered Elbow," having the words "Upper" and "Under," and the abbreviations "T. S." and "E," and the ditto-marks arranged as those in the columns directly above. 20 To the left of the tables just described are the tables for the wrist-measures of the common

sleeve and gathered elbow, marked "Wrist Measures," "Common Sleeve," "Upper" and "Under," and "Gathered Elbow," "Upper," 25 and "Under."

Having thus fully described my invention, what I claim as new, and desire to secure by Letters Patent of the United States, is— A pattern-chart having the curved slot V, 30 cut through the same, one wall of the slot having on one face the graduated scale 7 8 9, &c., and the corresponding face on the opposite side of the chart having points X Y 11, and the wall opposite thereto having the inclined line D F, as set forth.

In testimony that I claim the foregoing as my own I have hereto affixed my signature in presence of two witnesses.

SOPHRONIA T. LEWIS.
